UNITED STATES PATENT OFFICE

2,618,007

VACUUM CLEANER WITH NOZZLE AND DUST SEPARATING MEANS IN A COMMON HOUSING

Alfred H. Fuller, West Hartford, Conn., assignor to The Fuller Brush Company, Hartford, Conn., a corporation of Connecticut

Application April 26, 1947, Serial No. 744,066

7 Claims. (Cl. 15—347)

1

The invention relates particularly to vacuum cleaners of the type wherein the floor engaging nozzle is carried directly by a housing movable along the floor. The principal object of the invention is to provide in a vacuum cleaner of the stated type a simple and compact arrangement of parts wherein the dust separating means is located entirely within the main housing. The dust separating means is preferably a porous bag and when such a bag is provided it is located within the housing with its axis substantially horizontal and substantially parallel with the nozzle.

A further object of the invention is to provide various details of structure and arrangement by which the said more general object is attained.

Other objects of the invention will be apparent from the drawings and from the following description and claims.

In the drawings I have shown in detail a preferred embodiment of the invention, but it will be understood that various changes may be made from the construction shown, and that the drawings are not to be construed as defining or limiting the scope of the invention, the claims forming a part of this specification being relied upon for that purpose.

Fig. 1 is a plan view of a vacuum cleaner embodying the invention.

Fig. 2 is a right side view.

Fig. 3 is a sectional view taken along the line 3—3 of Fig. 4.

Fig. 4 is a sectional view taken along the line 4—4 of Fig. 3.

Fig. 5 is a sectional view taken along the line 5—5 of Fig. 3.

Figs. 6 and 7 are fragmentary sectional views similar respectively to Figs. 3 and 4 but showing a hose connection in lieu of a handle.

Referring to the drawings, 10 is a casing or housing which is generally rectangular in plan. The main body of the housing is preferably a casting of an aluminum alloy or other suitable light metal. The housing is supported by means of floor engaging wheels 12, 12 and 14, 14. Extending transversely of the casing near the front is a substantially vertical wall 16 which cooperates with the front wall 18 to provide a downward directed nozzle 20.

Extending transversely of the housing behind the wall 16 is a substantially vertical wall 22 which constitutes the front boundary of a chamber 24, the said chamber being bounded at the rear by the rear wall 26 of the housing, at the sides by the side walls of the housing, and at the

5 top by the top wall of the housing. The chamber is closed at the bottom by a separate sheet metal plate 28 which is suitably secured to the walls 22 and 26 and to the side walls. The chamber 24 is preferably a vacuum chamber and a vacuum is maintained therein by means of a motor and fan unit 30. The unit 30 is centrally positioned with its axis extending longitudinally and preferably somewhat inclined, as shown in Figs. 2 and 4. The unit 30 extends through and closely fits an aperture in the transverse wall 22. The fan 32 of the unit 30 is preferably at the rear, and when the motor of the unit is operated the fan is rotated to withdraw air from the chamber 24 and deliver it through the unit to the space at the front of the wall 22.

10 Positioned in the chamber 24 is a suitable dust separating means, this means preferably being a generally cylindrical porous bag 34. The length of the dust bag is substantially greater than its diameter. The bag 34 is closed at its left end and is open at its right end. It will be observed that the bag 34 is located entirely within the main housing 10 and is arranged with its axis horizontal and parallel with the transverse nozzle 20. The right wall of the housing has an opening corresponding in size to that of the bag 34, the edges of the bag engaging the periphery of the opening. The said opening in the side wall of the housing is normally closed by a hinged cover 36, this cover being normally held in closed position by a manually operable latch 38. The end of the bag 34 is provided with an annular flange which is engaged by the cover 36 when in closed position, the cover thus serving to hold the bag in place. When the cover 36 is opened the bag 34 can be readily removed for cleaning or replacement.

15 Means is provided for guiding air from the nozzle 20 to the interior of the dust bag 34. The said air guiding means preferably comprises ducts chiefly within the housing and formed integrally therewith. As shown, there is a main duct 40 which extends upward and rearward from the nozzle 20, the upper wall of the duct being the top wall of the housing. In order to provide sufficient space for the motor-fan unit 30, the main duct 40 preferably comprises two branches 42, 42 which are at opposite sides of the motor-fan unit. The main duct 40 communicates at its rear with a transverse duct 44. The air guiding means also includes a recess 45 in the cover 36 and the transverse duct 44 communicates with this recess 45. The cover 36 has an inner wall 46 with an opening therein which may be of the same

size as the cover, and it is this wall that engages the flange on the bag. The recess 45 is formed between the outer wall of the cover and the said inner wall 46. The wall 46 has an opening 47 therein with which the transverse duct 44 communicates. It will be seen that when the fan 32 is rotated to maintain a vacuum in the chamber 24, a flow of air is established from the nozzle 20 through the main duct 40, through the transverse duct 44, through opening 47 and the recess 45 and through the pores of the dust bag 34 into the vacuum chamber 24. Thus dust from the nozzle is withdrawn into the bag and there separated from the air.

A transverse rotatable brush is preferably provided in the nozzle 20 and as shown, the brush comprises two separate units 48, 48. The brush is so positioned that it projects slightly beyond the bottom of the nozzle so as to engage the floor. The details of the brush and of its mounting constitute no part of the present invention but as shown, the brush units are provided at their opposite ends with spring-pressed bearing pintles 50, 50 which engage bearing blocks 52, 52 carried by the side walls of the housing. For rotating the brush there is provided a worm wheel 54 positioned between the two brush sections 48, 48, this worm wheel 54 being engaged by a worm 56 on the shaft of the motor and fan unit 30.

The before-mentioned housing supporting wheels 12, 12 are positioned at the front of the dust bag 34 and are connected with the housing by means of inward projecting bearing pins 57, 57. The wheels 12, 12 are enclosed in hoods 58 and 59 which are open at the bottom and which are preferably formed integrally with the housing 10. The bottom plate 28 is shaped to fit around the contours of the hoods 58 and 59. The before-mentioned wheels 14, 14 are positioned at the rear of the dust bag 34 and preferably they are vertically adjustable with respect to the housing so that upon vertical adjustment of the wheels the housing is rocked about the axis of the wheels 12, 12 to change the relationship of the brush to the floor.

The wheels 14, 14 are mounted on a transverse pin 60 which engages two blocks 62, 62 spaced at equal distances from the longitudinal center line. Each block 62 is secured to a vertically movable pin 64 and springs 66 are provided for biasing the blocks for relative downward movement. The blocks 62 have ratchet teeth formed therein at the rear and two pivoted latches 68, 68 each having a tooth for engagement with the ratchet teeth of the corresponding block. The latches 68, 68 are connected for movement in unison and they are controlled by a spring-pressed finger piece 70. The center of gravity of the vacuum cleaner is behind the axis of the wheels 12, 12 and when the parts are in the positions shown in Fig. 4, the brush is in its lowermost position with respect to the floor. By pressing downward on the rear end of the housing the springs 66 may be compressed, the latches 68 engaging lower teeth on the blocks 62. Thus the brush can be raised with respect to the floor. In fact, by pressing the casing downward sufficiently to cause the latches 68 to engage the lowermost notches in the blocks 62, the brush may be raised so as to be entirely out of engagement with the floor. The brush may be lowered by moving the finger piece 70 to release the blocks 62 for relative downward movement.

The vacuum cleaner may be provided with a handle 72 by means of which it may be moved along the floor to effect cleaning. Preferably, the

rear end of the main duct 40 terminates in an opening in the rear wall of the housing, and the handle 72 is pivotally connected with a tubular member 74 adapted to be inserted in the said rear opening. The tubular member 74 may be held in place by an automatically engaging manually releasable latch 76. As will be apparent from Fig. 3, the tubular member 74 is open at the front and has a transverse wall 78 therein which is adjacent the rear edge of the transverse duct 44. The tubular member 74 has an opening 80 which provides communication with the said transverse duct. It will be seen that when the handle 72 and the tubular member 74 are in place, communication is established from the main duct 40 to the transverse duct 44 to enable the vacuum cleaner to operate in the manner already described.

It is sometimes desirable to attach a hose 82 which may be provided with a nozzle at its outer end in accordance with conventional practice. When such a hose is to be attached the handle 72 and its tubular member 74 are removed and a tubular member 84 attached to the hose is inserted in lieu of the tubular member 74, as shown in Figs. 6 and 7. The tubular member 84 is held in place by a latch 86 similar to the latch 76. The tubular member 84 is open at its outer end where it communicates with the hose. It is closed at or near its inner end by a wall 88 therein and it is provided with an opening 90 which communicates with the transverse duct 44. It will be seen that when the hose 82 and the tubular member 84 are in place air enters the transverse duct 44 from the hose rather than from the main duct 40 which is connected with the nozzle. Thus cleaning can be effected by means of the nozzle attached to the hose, the air being drawn through the dust bag for dust separation in the manner already described.

It will be seen that the interchangeable tubular members 74 and 84 constitute means associated with the rear end of the main duct and with the inner end of the transverse duct for establishing communication to the latter either from the main duct or from the exterior of the housing.

Preferably the space near the front between the walls 16 and 22 is closed at the bottom by a sheet metal plate 92. The chamber thus formed may be regarded as a pressure chamber and it has an opening 94 at one side thereof through which the air is discharged. If desired, a blower hose 96 may be connected at the opening 94 as indicated in Fig. 1.

From the foregoing description it will be apparent that the vacuum cleaner embodying the invention is simple and compact and has numerous advantages. The dust bag is enclosed within the main housing, and its position is such that a relatively large bag can be used in a relatively small housing. This is due to the arrangement with the axis of the bag horizontal and parallel with the nozzle and brush. The motor-fan unit is located within the casing and at the rear of the nozzle and brush and at the front of the dust bag. This places the motor in such a position that a simple and direct power connection to the brush may be provided, and it places the fan within the forward part of the vacuum chamber. The interchangeable handle and hose units provide for cleaning in the conventional manner by means of the nozzle and brush or by means of a nozzle on the hose, and

this is accomplished without any separate valve for changing the air connections.

The invention claimed is:

1. The combination in a vacuum cleaner, of a housing provided with a transverse downward directed nozzle near its front end, floor engaging means for supporting the housing, a transverse porous dust bag having its length substantially greater than its diameter, the said dust bag being located entirely within the housing with its axis substantially horizontal and substantially parallel with the nozzle, a motor within the housing at the rear of the nozzle and at the front of the dust bag, a fan within the housing adjacent the motor and driven thereby, and air guiding means associated with the fan for causing air withdrawn by the fan from the nozzle to be directed into the interior of the dust bag at one side of the housing, the said air guiding means including a main duct extending upward from the nozzle and then rearward along the top of the housing and also including a duct communicating with the rear portion of the main duct and extending therefrom transversely to one end of the dust bag at one side of the housing.

2. The combination in a vacuum cleaner as set forth in claim 1, wherein the motor is centrally located and wherein the main duct has two branches at opposite sides of the motor.

3. The combination in a vacuum cleaner, of a housing which is generally rectangular in plan and the main portion of which is a casting, the said housing being provided at its front with a transverse downward directed nozzle extending substantially from side to side thereof and having near its rear a vacuum chamber extending substantially from side to side thereof and the main portion of said housing having an integral transverse wall therein extending from side to side thereof and located between the nozzle and the vacuum chamber which wall has a central aperture therein, floor engaging means for supporting the housing, a transverse porous dust bag located entirely within the vacuum chamber and extending substantially from side to side thereof, the length of the dust bag being substantially greater than its diameter and the axis of the dust bag being horizontal and substantially parallel with the nozzle, a motor and fan unit within the housing and separate therefrom and surrounded thereby which unit is at the front of the dust bag and extends through and closely fits the aperture in the said transverse wall, the fan of the said unit serving to withdraw air through the unit to the front of the transverse wall so as to maintain a vacuum within the vacuum chamber, and means for guiding air from the nozzle to the interior of the dust bag at one side of the housing.

4. A vacuum cleaner as set forth in claim 3, wherein the means for guiding air includes a main duct integral with the main portion of the housing and extending upward from the nozzle and then rearward along the top of the housing and wherein the last said means also includes a duct extending transversely from the rear end of the first said duct and communicating with the interior of the dust bag at one side of the housing.

5. The combination in a vacuum cleaner, of a housing provided with a transverse downward directed nozzle near one end and having therein behind the nozzle a chamber extending sub-

stantially from one side thereof to the other which chamber has an opening at one side, floor engaging means for supporting the housing, a transverse porous dust bag located entirely within the said chamber in the housing with its axis substantially horizontal and substantially parallel with the nozzle, the edges of the bag engaging the periphery of the said opening at one side of the chamber, a motor within the housing at the rear of the nozzle and at the front of the dust bag, a fan within the housing driven by the motor, an openable cover for the said opening in the side of the chamber which cover has an interior recess therein communicating with the interior of the bag, and means associated with the fan for guiding air upward and then rearward from the nozzle and into the recess in the cover.

6. The combination in a vacuum cleaner as set forth in claim 5, wherein there is a main duct within the housing and integral with the main portion thereof and extending upward and rearward from the nozzle along the top of the housing and wherein there is a transverse duct integral with the main portion of the housing and communicating at one end with the rear of the main duct and communicating at the other end with the recess in the cover.

7. The combination in a vacuum cleaner, of a housing provided with a transverse downward directed nozzle near one end and having therein behind the nozzle a vacuum chamber extending substantially from one side thereof to the other which chamber has an opening at one side, floor engaging means for supporting the housing, a transverse porous dust bag located entirely within the said vacuum chamber with its axis substantially horizontal and substantially parallel with the nozzle, the edges of the bag engaging the periphery of the said opening at one side of the chamber, a motor within the housing at the rear of the nozzle and at the front of the dust bag, a fan within the housing driven by the motor and serving to maintain a vacuum within the vacuum chamber, an openable cover for the said opening in the side of the chamber which cover has an interior recess therein communicating with the interior of the bag, and means for guiding air upward and then rearward from the nozzle and transversely into the recess in the cover.
